UNITED STATES PATENT OFFICE.

RICHARD W. McEWAN, OF WHIPPANY, NEW JERSEY.

UNDERGARMENT.

1,128,702.

Specification of Letters Patent. Patented Feb. 16, 1915.

Application filed April 29, 1914. Serial No. 835,078.

To all whom it may concern:

Be it known that I, RICHARD W. McEWAN, a citizen of the United States, and a resident of Whippany, county of Morris, 5 and State of New Jersey, have invented certain new and useful Improvements in Undergarments, of which the following is a specification.

My invention relates to undergarments 10 and has for its object to provide a cotton, woolen or other knitted or woven undergarment with a friction reducing element or medium located at the knee portion of the drawers and also in some cases at the calf 15 portion thereof whereby the friction between the drawers and the trousers or adjacent portions of the legs of the wearer is reduced to a minimum and the trousers are prevented from sticking to the drawers when the 20 wearer assumes a sitting position or otherwise flexes the leg at the knee and the drawers comfortably adjust themselves to such changes in the wearer's position.

It is well known that with ordinary 25 woolen, cotton or other knit or woven undergarments a considerable frictional engagement exists between the underdrawers and the trousers particularly at the knee and the calf of the leg and that consequently, the 30 material of which the trousers are made is constantly subjected to objectionable stretching strains which distort the shape of said trousers and materially reduce their period of usefulness. Attempts have heretofore 35 been made to overcome these objectionable features by securing sheets or patches of material upon the surface of the garment at the knee portions thereof. Such arrangements however render the garment bulky at 40 these points and provide ridges above the surface thereof which increase rather than reduce friction and which materially interfere with the putting on and taking off of the garment.

45 The particular object of my invention is to overcome all of the above objections and to provide a comfortable undergarment without rendering the cost thereof prohibitive and without sacrificing any of the well 50 known advantages of a woven or knit woolen, cotton or similar undergarment.

My improvement will be fully described hereinafter and the features of novelty will be pointed out in the appended claims.

55 Reference is to be had to the accompanying drawing, which by way of example illus-

trates a front view of a pair of drawers with my improvement included therein, the illustration being more or less diagrammatic.

In the drawing, A represents the drawers 60 having legs B, and C and C' represent the element or medium located respectively at the knee and calf portions of the garment for reducing the friction between the drawers and the trousers to a minimum as 65 relative movement between the two takes place when the wearer assumes various different positions. The said element may be directly knitted or woven into the garment at the proper places during manufacture 70 and in some cases may be a tubular piece or insert extending completely around each leg, or in other instances the element may be a piece of woven, knitted, silk, satin or other fabric of suitable dimensions and having a 75 smooth or sleek surface, said pieces being in the nature of inserts properly and suitably fastened in said drawers so as to be substantially flush with the surfaces thereof.

The essential requirement in garments of 80 the type under consideration is the provision of smooth, sleek, or other frictionless surfaces at the knee or calf of the drawers or at both places, the said surfaces in some cases being merely exterior surfaces at the 85 indicated points and in other cases being both exterior and interior surfaces and at all times being substantially flush with the adjacent portions of the garment. The said element, no matter in what manner the same 90 is combined with the garment, may be diamond shaped as shown in the drawing or it may be of any other desired conformation most suitable for each particular instance or most desired by the particular 95 wearer. With such constructions the continuity of the surfaces of the garment is maintained and a complete absence of friction between the drawers and the trousers particularly at the knees and at the calves, 100 is secured, without sacrificing any of the warmth and other comforts or advantages of a complete knitted, or woven cotton, woolen or other undergarment. This is accomplished by making the garment or at 105 least the major portion thereof of woven or knitted wool, cotton or other material and providing the friction reducing element only at those points where it is most generally required and makes it possible 110 to produce an undergarment having a maximum of serviceability and comfort at a

minimum cost. It will readily be apparent that as the wearer assumes a sitting position or flexes the leg during other movements of the body that the trousers will readily 5 slide over the element C or C' with a minimum of friction so that stretching strains are removed and the trousers consequently do not bag at the knees and are not otherwise distorted and thus retain their shape 10 for an increased period so that the life and usefulness thereof is thus prolonged. As stated above it may sometimes be desirable to provide an interior as well as an exterior frictionless surface, the former contracting 15 with the skin of the wearer and permitting the underdrawers to adjust themselves relatively to the skin of the wearer with a minimum degree of friction and with a consequent minimum strain on the fabric and a 20 maximum degree of comfort to the wearer. In cases where both interior and exterior surfaces are provided, for instance by means of a material napped to a greater or lesser degree such as satin, the nap on the outer 25 surface is arranged to lie in one direction while the nap on the inner surface lies in the opposite direction. It will of course be understood that the lay of the nap will in each instance be in a direction to present

the least resistance to a relative adjustment 30 of the garment.

My invention is equally well adapted for either two piece or union undergarments and with drawers of any length from full length to knee length. 35

Various changes in the specific form shown and described may be made within the scope of the claims without departing from the spirit of my invention. 40

I claim:

1. An undergarment provided at predetermined portions thereof with sections of relatively antifriction material substantially flush with the adjacent portions of the garment. 45

2. An undergarment provided at the knee portions with inserts of relatively smooth antifriction material such as silk or similar fabric, said inserts being substantially flush with the adjacent portions of the garment. 50

In testimony whereof I have hereunto set my hand in the presence of two subscribing witnesses.

RICHARD W. McEWAN.
